UNITED STATES PATENT OFFICE.

CLARENCE P. COOK, OF WATERBURY, CONNECTICUT, ASSIGNOR TO SCOVILL MANUFACTURING COMPANY, OF WATERBURY, CONNECTICUT, A CORPORATION OF CONNECTICUT.

VANITY BOX.

Application filed January 13, 1927. Serial No. 160,845.

This invention relates to certain improvements in vanity boxes and particularly to a vanity box construction by which a compact may be readily removed from the box.

In certain types of vanity boxes, that is, the small boxes now commonly used for carrying cosmetics, the cosmetic is carried in the form of a compact. These compacts are of powder or rouge, which are moulded or compacted onto a base, these bases being inserted in the box. In certain types of boxes, for neatness of appearance, the compacts are inserted in a fitment suitably secured in the body of the box, the compact being held in the fitment by snapping it under lugs or projections carried by the fitment. In many cases, it is desirable to remove these compacts from the box and, where they are held by projections, difficulty has been experienced in freeing the compact plate or tray from the holding projections. Various ejecting devices have been proposed for doing this, which are arranged to underlie the compact and are provided with a removable part, upon the movement of which the compact is ejected from the box. These ejecting devices are objectionable, in that they add to the expense of making the box and the manually operable parts are unsightly and detract from the neat appearance of the box.

It is the especial object of the present invention to produce a box construction in which a compact is securely held in the box, but which may be removed from the box by the insertion of a pin or other suitable tool through the box body when it is desired to remove the compact.

A further object of the invention is to produce such a box of attractive appearance and one in which the opening through which the tool is inserted is rendered inconspicuous.

With these and other objects not specifically referred to in view, the invention consists in certain novel parts, arrangements and combinations which will be described in connection with the accompanying drawings and the novel features pointed out in the claims hereunto annexed.

In these drawings,—

Figure 1 is a bottom view of the box embodying the invention;

Figure 2 is a face view of a box opened with the compact removed;

Figure 3 is a sectional view, partly broken away, taken on the line 3-3 of Fig. 2 showing the compact in position, and

Figure 4 is a view similar to Fig. 3 showing the removal of the compact.

Referring now to these drawings, the box chosen to illustrate the invention is square in shape, having a body 1 and a cover 2 pivotally associated therewith on a hinge 3 of any conventional type. While the box has been shown as square, it will be understood that the invention is applicable for use in boxes of any desired shape. Mounted in the body of the box is a fitment 4 having a side flange 5 in close frictional engagement with the wall of the body. This fitment is exteriorly substantially the shape of the body and is provided with a central opening 5 formed by turning in the inner edge of the fitment to form vertical side walls 7 and a bottom ring or annulus 8. This forms in effect a well, which in the particular construction shown is circular.

The inner walls of the well, above the annulus 8, are provided with holding projections 9, which are readily formed by bending in the metal of the fitment, as shown in Fig. 3, four such projections being shown, see Fig. 2. The powder compact, indicated at 10, is carried on a base 11 which may be formed with side walls 12 which extend upwardly from the base. This compact is held in position in the body by the pressure of the resilient projections bearing on the walls of the plate, which, as shown, extend in under the projections, and the compact is thus firmly secured.

In accordance with the invention, the box is so constructed that the compact plate may be readily removed from engagement with the projections so that a new compact may be inserted in the box, and these means are such as to add no further parts, due to construction. As shown, the bottom of the box is provided with one or more small apertures 13 through which a pointed tool, as a pin 14, may be inserted. By pressing this tool against the plate, the compact may be readily forced past the projections and thus become freed from the fitment. This construction adds no parts to the construction of the box and affords a very simple and efficient way of removing the frictionally held compact. For neatness of appearance, the

body of the box around the holes or apertures will be formed with surface ornamentation, indicated at 15 in Fig. 1, so that the holes will be rendered less clearly visible, though this ornamentation is not essential and can, if desired, be omitted, the holes themselves being made so small as to be not undesirably conspicuous.

It will be understood, of course, that the shape of the box and the shape of the fitment may be widely varied and the invention is not to be restricted to the form of box and fitment shown.

What I claim is:

15 1. In a vanity case, the combination of a body and a cover therefor, a compact holding fitment in the body, holding projections on the fitment below which the edge of the compact engages, when in place in the fit-

ment, and an aperture in the bottom of the box below the compact through which a tool may be inserted from without the box to force the compact past the projections. 20

2. In a vanity case, the combination of a body and a cover therefor, a compact holding fitment in the body, holding projections on the fitment below which the edge of the compact engages, when in place in the fitment, an aperture in the bottom of the box below the compact through which a tool may be inserted from without the box to force the compact past the projections, and surface ornamentation about the aperture to render it less conspicuous. 25

In testimony whereof, I have hereunto set my hand. 30

CLARENCE P. COOK.
